UNITED STATES PATENT OFFICE

EDWARD J. DACEY, OF PHILADELPHIA, PENNSYLVANIA, ASSIGNOR TO CROMPTON & KNOWLES LOOM WORKS, OF WORCESTER, MASSACHUSETTS, A CORPORATION OF MASSACHUSETTS

STATIONARY WIRE WILTON LOOM

Application filed May 3, 1929. Serial No. 360,229.

This invention relates to looms for weaving Wilton pile fabrics and it is the general object of the invention to provide mechanism which will operate to wrap the pile forming yarn around the pile wire in a continuous coil.

Such fabrics as Wilton carpets may be woven either on the so-called side wire or stationary wire loom. In the side wire loom a long wire is inserted between the separated planes of weft below the pile forming warp threads but above the dead pile. The wire extends transversely across the fabric and the piles take the form of a sinuous thread running lengthwise of the fabric. In stationary wire looms, on the other hand, the pile wire usually extends through the reed longitudinally of the fabric and it is necessary to effect a crossing of the pile forming threads from one side to the other of the stationary pile wire. In the usual stationary wire loom the yarn for forming any given tuft will cross the pile wire twice, moving first in one direction to form half the tuft and then moving in the other direction to form the other half of the tuft.

It is necessary that the yarn be drawn from the same side of the stationary pile wire by the jacquard when selected to form pile and it is this fact which requires the double crossing of the yarn. For instance, the yarn may rise on the left hand side of the pile wire and be crossed over in a right hand direction and down on the right hand side of the pile wire. A pick of filling is then laid over the active pile yarn and under the pile wire. If the operation of forming the pile stopped at this point the active pile yarn would be in the wrong position to be lifted at a subsequent call and it is for this reason that the piles must be crossed again, going from the right to the left hand side of the pile wire over the latter and then depressed so that a second pick of filling may be inserted over the active pile and under the pile wire.

This double operation leaves the pile yarn in proper position to be raised when called again. It will be understood that for the formation of each pile therefore it is necessary for the active pile forming yarn to cross

the pile wire twice and in order that this result may be accomplished it is customary to have the pile yarn of half the size of that employed in side wire looms where a single crossing of the transverse pile wire is sufficient to form the pile and where the necessity for placing the pile yarn on the right side of the pile wire does not arise.

It is an important object of my present invention to provide means for looping the active pile around the pile wire in the form of a continuous coil so that a single movement of the pile yarn from the left side of the wire over the latter and down on the right hand side of the pile wire will be sufficient to form a complete loop or pile, the pile yarn being restored to its proper position on the correct side of the pile wire by a single revolution around the latter. In this way I am enabled to produce a complete pile with a single passing of the yarn and therefore much more quickly than is possible in present methods.

It is a further object of my present invention to provide on the hand rail of the lay a laterally moving reed effective to move the pile yarn from one side to the other of the pile wire and then to return the pile forming yarn to its original position while under the pile wire.

With these and other objects in view which will appear as the description proceeds my invention resides in the combination and arrangement of parts hereinafter described and set forth in the claims.

In the accompanying drawings wherein I have shown one form of mechanism for carrying out my present invention,

Fig. 1 is a vertical longitudinal section through a loom having my invention applied thereto,

Fig. 2 is a horizontal section on line 2—2 of Fig. 1,

Fig. 3 is an enlarged view looking in the direction of arrow 3, Fig. 1,

Fig. 4 is an enlarged longitudinal section of the fabric showing the relation between the pile wire and the pile yarn, indicating the latter as being wrapped in the form of a helix or coil around the pile wire, and

Fig. 5 is an enlarged sectional view through the hand rail and associated parts, certain parts being omitted.

Referring particularly to Fig. 1, I have shown a loom frame 10 and a lay 11 movable back and forth in the loom frame around an axis 12. The loom has a breast beam 13 with a cross bar 14 to hold pile wires 15 in position. I do not wish to be limited to any particular form of pile wire but it is desirable to have some form of cutter indicated at 16 integral with the pile wire and effective to cut the loops of pile yarn which extend over the pile wire during the weaving operation.

The pile wire has a rearwardly extending portion 17 which is preferably inclined upwardly as set forth in Fig. 1. It is to be understood that there are a set of pile wires 20 extending across the loom, one preferably for each reed space and the forward ends of said pile wires are held in position rigidly against displacement in the direction of the length of the fabric being woven as well as laterally thereof.

The lay is provided with a reed 18 and a hand rail 19 secured to the lay in any approved manner and moving back and forth with the latter. As shown in Figs. 1 and 2 the hand rail is provided with guides 20 in which moves a rack member 21 in a direction parallel to the length of the hand rail. Said member is confined to the guide members 20 by gib 22 and the rack is provided with teeth 23 at one end thereof to mesh with a pinion 24. The latter is secured to the upper end of a shaft 25 which extends through upper bearing 26 and lower bearing 27 secured to and moving with the lay.

The rack has depending therefrom a plurality of fingers 28 which are spaced apart the same distance as are the wires of the reed 18. These fingers 28 will extend downwardly a short distance and terminate at points above the straight slightly inclined rear extensions 17 of the pile wires. The fingers move laterally with respect to the reed 18 when the rack 21 is caused to move along the hand rail 19.

Means for effecting lateral movement of the rack 21 include a beveled pinion 29 secured to the lower end of the shaft 25. This beveled pinion meshes with a beveled segment 30 pivoted as at 31 to a fixed axis. A connector 32 is attached to the segment as at 33 at its forward end and at its rearward end is connected as at 34 to a lever 35 pivoted as at 36 to a fixed support. The lever carries a roll 37 which engages a cam 38 and said lever is acted upon by a spring 39 in such a way as to hold the roll 37 against the face of cam 38. The cam is provided with two high surfaces 40 between which are located relatively low surfaces 41.

Binder confining devices in the form of

heddles 42 are provided with elongated eyes 43 which are held vertical by means of lin-goes 44. The heddles are connected at their upper ends to fixed supports 45 and are capable of slight lateral movement with respect to the reed. The eye 43 of each heddle 42 has passing therethrough a pair of binder threads B and it is to be understood that there will be one heddle eye for each reed space, each of the latter being occupied by two binders.

The rearward extension 17 of each pile wire is provided with an upstanding arm 46 the upper end of which projects above a line passing through the fell of the cloth and the lower end of the corresponding finger 28 on the rack 21.

In the operation of my invention the selected pile yarn P which is to form the surface of the finished fabric will be raised by the jacquard not shown to the point indicated in Fig. 1 above the lower ends of the fingers 28 and the arms 46. The driving mechanism for the shaft 25 will be so timed that the rack 21 will be given a movement to the right after the pile yarn P has been raised. The fingers 28 will therefore engage the active pile yarns and move the same from the left to the right hand side of the pile wire as viewed in Fig. 2. The jacquard will then operate to lower the active pile yarn and the latter will pass below the tops of the arms 46 before they are released by the fingers 28, the arms 46 operating in this way to insure movement of the pile yarn down on the right hand side of the pile wire.

As soon as the active pile yarn moves to a position below the fingers 28 it will tend by its elasticity to move back to its normal position which is to the left hand side of the pile wire. The arms 46, however, will restrain this movement until the active pile yarn has moved below the pile wire, after which the pile yarn will spring back to the left hand side of the pile wire. Meantime the shaft 25 has been acted upon to shift the rack 21 to the left or back to its original position. A shot of filling will now be laid over the active pile yarn and under the pile wire, after which the active pile yarn will again be raised by the jacquard and the operation previously described repeated so long as the same color is to remain active in the reed dent under consideration.

When a change in the active pile is to occur the pile forming yarn which is to be retired will upon moving down below the pile wire spring back to the left of the pile wire in the usual manner and will then become dead or be buried in the fabric, and another of the color yarns which is to become active pile will be raised from the left hand side of the pile wire to be acted upon by the fingers 28 in the manner already described.

The binder threads B may be manipulated

in the usual manner and are placed in the heddles 43 so as not to become entangled with the active pile yarn when the latter is being looped around the pile wire.

5 From the foregoing it will be seen that I have provided mechanism for wrapping each active pile yarn around its corresponding pile wire in the form of a coil so that a single crossing over the top of the pile wire is sufficient to form a complete tuft. It will also be seen that this control of the active pile is facilitated by the rack and fingers 28 which move on the hand rail, said fingers acting to move the pile yarn from their normal position on one side of the pile wire to a position on the other side of the pile wire. The bevelled segment moves about a point which is very close to the axis of the lay so that the rocking of the lay back and forth has very little if any effect on the movement of the rack with respect to the hand rail. Any movement which may result on the part of the rack incident to the normal operation of the lay may be corrected by properly forming the surface of the cam which rocks the bevel segment.

Having thus described my invention it will be seen that changes and modifications may be made therein by those skilled in the art without departing from the spirit and scope of the invention and I do not wish to be limited to the details herein disclosed, but what I claim is:

1. In a pile fabric loom, a stationary pile wire extending longitudinally of the fabric being woven and having a free rear end, a lay having a hand rail, a rack movable along the hand rail, fingers movable with the rack to engage the active pile yarn, means to move the rack laterally with respect to the lay to shift the active pile yarn from one side to the other side of the pile wire, said fingers being of such length that as the active pile yarn moves downwardly it will pass out of control of the fingers and when below the pile wire be free to move back to its original position.

2. In a pile fabric loom, a lay movable therein, a stationary reed mounted on and movable with the lay, a normally stationary pile wire extending through the reed and having an upturned portion at the rear end thereof, and an auxiliary reed movable relatively to the stationary reed and having a portion thereof lying below a line passing through the fell of the fabric and the upturned rear end of the pile wire, said auxiliary reed lying between the stationary reed and the upturned end of the pile wire.

3. In a pile fabric loom having a lay, a stationary reed mounted on and movable with the lay, a handrail supported by the lay, an auxiliary reed normally stationary but movable transversely of the movement of the lay and the first named reed and mounted on the handrail behind said first named reed,

normally stationary pile wire around which the pile is woven, said wire having a portion extending rearwardly through the stationary reed and beyond the auxiliary reed, said rearwardly extending end of the pile wire having an upturned portion to guide the pile yarn as the latter is woven over the pile wire. 70

4. In a pile fabric loom having a lay, a pile wire around which the pile yarn is woven, said lay having a stationary reed through which the pile wire extends, a hand rail supported by the lay and having an auxiliary reed mounted for a transverse movement thereon, a rack and pinion to move the auxiliary reed, a segment and gear to give 80 movements to the rack and pinion, connections between the segment and gear, and rack and pinion, means to give the segment and gear an oscillating movement, said movement of the segment being transmitted 85 through the connections to the rack and pinion to give the second reed its transverse movement.

5. In a pile fabric loom, a lay movable back and forth therein, a reed secured to said lay 90 and held against movement laterally of the lay, a second auxiliary reed mounted on the lay and capable of lateral movement relatively to the lay and first named reed, said auxiliary reed located behind the first named 95 reed, and a pile wire extending from the front of the lay through the first reed and terminating behind the auxiliary reed, said pile wire having an arm rearwardly of the auxiliary reed, and the latter moving to move a 100 pile warp from one side to the other of said arm.

6. In a pile fabric loom having binder threads and pile yarn, a lay having a stationary reed thereon, a hand rail supported 105 by the lay, an auxiliary reed mounted on the hand rail behind the stationary reed to have a movement transverse of the movement of the lay, a normally stationary pile wire extending through the reed and having at its 110 rear end an upturned portion to guide the pile yarn, transverse movement of the auxiliary reed moving the pile yarn from one side of the pile wire to the other, and a device independent of the lay and reed and through 115 which the binder threads extend and are kept from becoming entangled with the pile wire, said device lying to one side of the pile wire.

In testimony whereof I have hereunto af- 120 fixed my signature.

EDWARD J. DACEY.
